UNITED STATES PATENT OFFICE.

FRANK J. ROGERS, OF INDEPENDENCE, KANSAS, ASSIGNOR OF ONE-HALF TO OWEN ALONZO THOMPSON, OF INDEPENDENCE, KANSAS.

SACK GRIP.

Application filed January 10, 1925. Serial No. 1,685.

To all whom it may concern:

Be it known that I, FRANK J. ROGERS, a citizen of the United States, residing at Independence, in the county of Montgomery 5 and State of Kansas, have invented certain new and useful Improvements in Sack Grips, of which the following is a specification.

This invention relates to improvements in 10 sack grips and has for its object to provide a device somewhat in the form of a mitten having means for securely gripping a sack, to be handled by the wearer.

Another object of the invention is to provide a flexible sack grip having a palm-piece with a number of pin points projecting therefrom for projecting into the sack material.

A still further object of the invention is 20 to provide a sack grip and a guard to which the same is hingedly connected and means for quickly securing the grip to the guard.

With the above and such other objects in view as may hereinafter more fully appear, 25 I have invented the device illustrated in the accompanying drawings in which:

Figure 1 is a plan view of my sack grip, shown attached to the hand and wrist of the wearer;

30 Figure 2 is a similar view showing the grip detached from the hand and secured to the guard;

Figure 3 is an enlarged plan view of the device shown open;

35 Figure 4 is a similar view, a reinforcing member being removed;

Figure 5 is a section on line 5—5 of Figure 3; and

40 Figure 6 is a detail plan view of the grip, the hand straps being thrown back.

Like reference characters indicate like parts throughout the following specification and in the several views in the drawings in which 1 indicates a hand grip consisting 45 of a guard member 2, and a grip member 3 hingedly connected together at 4 by means of a hinge lacing 5, threaded through the eyes 6 of the member 4 and 7 of the member 3, the hinge edges 8 and 9 of the members 2 and 3 being rounded in order to operate smoothly. The outer face 10 of the member 3 has projecting there-through a plurality of pin points 11, the heads 12 of which are held in place by means of a shield 55 13, substantially covering the inner surface

14 of the member 3 and being laced through the means of the lacing 15 whereby it may be removed when desired to replace worn out pins.

The opposing sides of the member 13 are 60 cut away at 16 and 17 for the accommodation of the straps 18 and 19, one end of each of which is stitched to the edges 20 and 21 of the member 3. The free ends of these members 18 and 19 are provided with a 65 buckle and strap connection 24, forming a hand loop 25 through which the hand 26 may be quickly projected, or as quickly removed. An extension 27 is provided on one side of the member 3 to which the thumb 70 guard 28 is secured. To this guard is fixed a snap member 29 for engagement, when desired, with the snap member 30 on the strap 31, projecting from the edge 32 of the guard 2. To the inner surface of said guard 2 is 75 fixed a pair of straps 33 and 34 forming a wrist band 35 having a strap and buckle connection 38 whereby said wrist band may be secured to the wrist 39 of the wearer.

In lifting heavy sacks such as those containing cement, guano, grain, etc., and especially those in which a small gripping projection is provided it is difficult to get a secure hold on the same. Especially is this the case where the sack is sewed which is 80 the common custom now, instead of being tied as was formerly the custom. I have also found that the effort to hold the sack creates a very great strain upon the muscles of the arms and fingers of the operator and it was with a view of overcoming this difficulty and making it possible to work much faster in manually transferring these sacks, that I have provided the above described 85 sack grip with which I have found that 90 sacks of the nature referred to may be gripped and held securely with little or no difficulty. It is to be understood that these grips are used in pairs, one for each hand.

In order to avoid the necessity of un-buckling the grip from the wrist of the user whenever it is desired to operate a hand truck which has been loaded with heavy sacks, I have provided the hinge connection of the grip 3 to the guard 4, and the snap 100 connection between these members so that the operator may quickly remove his hand from the hand band 40, formed by the straps 18 and 19 and snap the members 29 and 30, whereby the member 2 may be held up out 105 110

of contact with the hand of the wearer so that the hand may be free in order to manipulate said truck. In order to hold the members 3 and 13 securely together at the center portion to prevent the shoving of the pin points 11 out of place, I have provided a stiffener, 41, on the member 13 to which the member 2 is rigidly fixed by means of bolts 43 and 44.

10 The above described device is preferably made of leather, however, it is to be understood that it may be made of any other suitable material.

Having described my invention that which 15 I claim to be new and desire to procure by Letters Patent is:

1. A device of the character described consisting of a palm member having a series of pin points projecting therefrom, means for holding said pins against displacement, said means consisting of a detachable backpiece.

2. A device of the character described consisting of a palm member having a series of pin points projecting therefrom, means for 25 holding said pins against displacement, said means consisting of a detachable backpiece, laced to said palm piece.

3. A device of the character described consisting of a palm member having a series of 30 pin points projecting therefrom, means for holding said pins against displacement, said means consisting of a detachable backpiece, laced to said palm piece, and means for holding said back piece and palm member to one another.

4. A device of the character described consisting of a palm member having a series of pin points projecting therefrom, means for holding said pins against displacement, said 40 means consisting of a detachable backpiece, laced to said palm piece, and means for holding said back piece and palm member to one another, means for attaching said palm piece to the hand of the wearer.

45 5. A device of the character described consisting of a palm member having a series of pin points projecting therefrom, means for holding said pins against displacement, said means consisting of a detachable backpiece,

laced to said palm piece, and means for 50 holding said back piece and palm member to one another, means for attaching said palm piece to the hand of the wearer, a guard member to which said palm member is hingedly connected. 55

6. A device of the character described consisting of a palm member having a series of pin points projecting therefrom, means for holding said pins against displacement, said means consisting of a detachable backpiece, 60 laced to said palm piece, and means for holding said back piece and palm member to one another, means for attaching said palm piece to the hand of the wearer, a guard member to which said palm member is hingedly connected, means for securing said 65 guard member to the wrist of the wearer.

7. A device of the character described consisting of a palm member having a series of pin points projecting therefrom, means for holding said pins against displacement, said means consisting of a detachable backpiece, 70 laced to said palm piece, and means for holding said back piece and palm member to one another, means for attaching said palm piece to the hand of the wearer, a guard member to which said palm member is hingedly connected, means for securing said guard member to the wrist of the wearer, means for detachably connecting said palm 75 member and guard member. 80

8. A device of the character described consisting of a palm member having a series of pin points projecting therefrom, means for holding said pins against displacement, said 85 means consisting of a detachable backpiece, laced to said palm piece, and means for holding said back piece and palm member to one another, means for attaching said palm piece to the hand of the wearer, a guard member to which said palm member is hingedly connected, means for securing said guard member to the wrist of the wearer, means for 90 detachably connecting said palm member and guard member, a lace forming said hinge. 95

In testimony whereof I affix my signature.
FRANK J. ROGERS.
